UNITED STATES PATENT OFFICE.

ADNA A. WADSWORTH, JR., OF NEW YORK, N. Y., ASSIGNOR OF ONE-FOURTH TO
GEORGE E. MERRIFIELD AND ONE-FOURTH TO CHARLES T. STUART, BOTH
OF NEW YORK, N. Y.

TOILET-CASE.

1,280,907.

Specification of Letters Patent.

Patented Oct. 8, 1918.

Application filed November 3, 1917. Serial No. 200,129.

To all whom it may concern:

Be it known that I, ADNA A. WADSWORTH, Jr., a citizen of the United States of America, residing at New York, in the county of 5 New York and State of New York, have invented new and useful Improvements in Toilet-Cases, of which the following is a specification.

Travelers in hurriedly packing up to leave 10 for a certain destination often-times forget one or more of their toilet articles.

It is the primary object of this invention to provide a case for these articles, constructed to render it exceedingly awkward to close 15 the case until every article is in its respective place therein, thus making it less possible for the person to forget any of such articles.

To this end the invention consists of a device of this character wherein each of the 20 holders in the case for the various articles has associated therewith a means adapted to be automatically released upon removal of an article from the case to retain the cover of the case open until the article is replaced 25 in its proper position in the case.

Another important object flowing from the invention resides in the provision of a means for this purpose adapted to engage the articles to hold the same under tension 30 within their respective holders, with a view of preventing casual displacement or separation of the same therefrom under any circumstances.

Another object of the invention resides in 35 the provision of a means which will be adjustable to readily accommodate itself to articles of different sizes.

Other objects will appear as the nature of the invention is better understood, the same 40 residing in the construction, combination and arrangement of parts hereinafter more fully described.

In the drawings, forming a part of the application, like numerals of reference indicate 45 similar parts in the several views, and in which:

Figure 1, is a perspective view of the case folded.

Fig. 2, is a view of the same unfolded.

50 Fig. 3, is a section on the line 3—3, of Fig. 2.

Referring more particularly to the drawing, the case essentially consists of a back 5,

end flaps 6, side flaps 7, and a retaining flap 8, all of which being adapted to be folded 55 upon one another to provide a substantially rectangular casing as shown in Fig. 1. The several flaps described are provided with suitable fastenings 9, whereby they may be connected together and the case held in a 60 closed position as shown in the mentioned Fig. 1. I aim principally to provide a structure in which the several flaps can be readily folded together in package or case form and will be arranged substantially in the same 65 general horizontal line when unfolded as shown in Fig. 2. Any suitable well-known structural formation can be resorted to provided the function described above can be accomplished. However, it is desired that 70 the case as a whole be constructed of an intermediate stiffening material 10, an inner lining 11, and an outer covering material 12. This arrangement gives good results in that the package is rendered strong and durable, 75 it is cheap in cost and yet can be conveniently carried on the person.

Extending along the longitudinal center of the wall 12' is a narrow strap 13, the end 80 14, of which being suitably secured in any well-known manner to said wall 12', and then passed through loops 15, which are secured to said wall 12', the free end 16, of the strap being extended against the inside of the next adjacent flap 6, whereby it may be manipulated and the strap tensioned or adjusted as the occasion necessitates. In this manner 85 loop shaped holders are formed for the reception of the articles to be accommodated in the case. The arrangement also provides 90 means whereby articles of different sizes can be uniformly accommodated. The strap 13, is held in an adjusted position through frictional contact thereof with the loops 15. Secured to the wall 12', adjacent the 95 loop-like holders for the toilet articles are inner sections 17, of fingers 18. Each of said fingers is hingedly connected at 19 with its sections 17, and as illustrated a spring 20, is employed for normally exerting pressure 100 against the finger. The finger 18, is adapted to overlie the mentioned section 17, under normal conditions. In this manner it is evident that the loop holders formed by the strap 13, are held under some tension, the articles contained in said holders 105

being pressed against the walls of the latter under the action of the springs 20, which operate to force the fingers 18, yieldingly against the articles. It is always preferred 5 that at least one finger be provided for each article holder or loop, so that no matter what article is removed from the case, one of said fingers will automatically fly back upon releasing of same, opening the next 10 adjacent side flap 7, thus making it very awkward to close the case until every article is in its respective holder. The attention of those using the case by reason of this construction will thereby be directed to 15 the absence of any article in hurriedly packing to leave for a certain destination. The fingers are so arranged that they completely come over the joint between the wall 12' and said next adjacent flap 7 and the latter is 20 held in the same general horizontal line with said wall 12', when an article is removed from its holder.

Any suitable arrangement of holders can be resorted to as for instance, straps 21 are 25 very conveniently arranged upon one of the flaps 7, and associated with a resilient finger 22, whereby to receive the toilet article as illustrated herein. Again, straps such as those shown at 23, are very nicely accommodated on the back 5, and are adapted respectively to receive different articles such as a razor and comb. These last straps are also combined with resilient fingers 24, which operate under normal conditions to 35 hold the articles in their respective holders.

It is believed that from the foregoing description the nature and advantages of the invention will be thoroughly understood without requiring a more extended explanation, and therefore the same has been omitted.

However, I desire to have it understood that I do not limit myself to the precise construction and arrangement illustrated and 45 described and that various changes in this

respect may be resorted to when desired as fall within the scope of the appended claims.

What I claim is:

1. A toilet case having foldable flaps, and means arranged interiorly of the case and automatically released upon removal of an article therefrom to retain one of said flaps in extended position. 50

2. A toilet case having foldable flaps, and a resilient finger secured interiorly of the case and adapted to be automatically released upon removal of an article therefrom to retain one of said flaps in extended position. 55

3. A toilet case having foldable flaps, a strap secured to the interior of the case and formed to provide loops for the reception of articles, resilient fingers secured to the case and extended to be engaged by the articles whereby the latter are held under tension in 60 their respective holders, and said fingers being adapted to be automatically released upon removal of said articles to retain one of said flaps in extended position. 65

4. A toilet case having foldable flaps, a strap arranged interiorly of the case and adjustable therein and provided with loops adapted to receive articles therein, and means in the case adapted to be automatically released upon removal of an article 70 from its holder to retain one of the flaps in extended position. 75

5. A toilet case having foldable flaps, a strap arranged interiorly of the case and adjustable therein and provided with loops 80 adapted to receive articles therein, means in the case adapted to be automatically released upon removal of an article from its holder to retain one of the flaps in extended position, and comprising resilient devices 85 extending directly across the joints between the next adjacent flaps when said case is opened.

In testimony whereof I affix my signature.

ADNA A. WADSWORTH, JR.
